DESIGN FOR A DOLL

Patricia Anne Hawes, Orange, Calif.

Application April 5, 1948, Serial No. 145,542

Term of patent 3½ years

(Cl. D34—4)

To all whom it may concern:

Be it known that I, Patricia Anne Hawes, a citizen of the United States, residing at Orange, in the county of Orange and State of California, have invented a new, original, and ornamental Design for a Doll, of which the following is a specification, reference being had to the accompanying drawing, forming part thereof.

I claim:

The ornamental design for a doll, substantially as shown.

PATRICIA A. HAWES.
